CLAIM

The ornamental design for a face mask nose bridge dam, as shown and described.

DESCRIPTION

FIG. 1 is a front perspective view of the face mask nose bridge dam showing my new design;

FIG. 2 is a back view thereof;

FIG. 3 is a top view thereof;

FIG. 4 is a side view thereof;

FIG. 5 is a bottom view thereof; and,

FIG. 6 is a front perspective view showing placement with a face mask.

The broken line showing of the human face and mask in FIG. 6 depicts environmental subject matter and forms no part of the claimed design.
